UNITED STATES PATENT OFFICE.

WILLIAM MALLINSON, OF HALIFAX, ENGLAND, ASSIGNOR TO JOSEPH WILD & CO., OF NEW YORK, N. Y.

DESIGN FOR CARPETS.

Specification forming part of Design No. 6,260, dated November 19, 1872.

To all whom it may concern:

Be it known that I, WILLIAM MALLINSON, of Halifax, in the county of York, England, have invented a new and original Design for a Carpet, of which the following is a specification:

The accompanying photograph fully illustrates my new design.

This invention relates to a new design for a carpet, in which there is arranged a star-shaped central ornament surrounded by and set into a groundwork of oak leaves and

branches. Between every four such groups of stars is placed a smaller group, whose center is a small cross, which is surrounded by fern-like leaves and branches, all as shown in the photograph.

I claim as my invention—

The design for a carpet, as shown.

WILLIAM MALLINSON.
